UNITED STATES PATENT OFFICE.

JOSEPH E. PERRAULT AND MALCOLM S. CATE, OF WATERTOWN, MASSACHUSETTS, AS-SIGNORS TO HOOD RUBBER COMPANY, OF WATERTOWN, MASSACHUSETTS, A CORPORATION OF MASSACHUSETTS.

BEAD-CORE-BUFFING MACHINE.

Application filed November 10, 1924. Serial No. 748,896.

To all whom it may concern:

Be it known that we, JOSEPH E. PERRAULT and MALCOLM S. CATE, citizens of the United States, and residents of Watertown, in the county of Middlesex and State of Massachusetts, have invented certain new and useful Improvements in Bead-Core-Buffing Machines, of which the following is a specification.

10 Our said invention relates to a machine for buffing the endless bead core rings such as are, used in reinforcing the edges of straight side pneumatic tires, which, as well understood by those skilled in the art, comprise inextensible cores (usually of braided wire) covered with rubberized fabric, such rings being of endless circular form and of more or less resilient nature, and capable of being distorted from their true circular condition.

15 Said invention aims to provide a simple, economical, and efficient apparatus capable of being easily manipulated.

With these and other objects in view, the 20 invention includes the novel features of construction and arrangement and combination of parts hereinafter defined by the appended claims.

An embodiment of our invention is illustrated in the accompanying drawings, in 25 which—

Figure 1 is an end elevation of a buffing machine constructed in accordance with our invention.

30 Fig. 2 is a front elevation.

Fig. 3 is an elevation looking in the opposite direction from Fig. 1.

35 Figs. 4, 5, and 6 are partial elevations corresponding to Figs. 1, 2, and 3, respectively, 40 but showing the parts in feed and buffing position.

Referring by reference characters to these drawings, the numeral 1 designates driving means such as a belt operated from any suitable source of power (not shown) which 45 passes around the drive pulley 3 fast on the main drive shaft 4 journaled in suitable spaced bearings 6 in the main frame of the machine. 5 designates a hollow swinging 50 brush-carrying arm having one end journaled or pivotally mounted on said shaft

between said bearings, and having journaled in its free end a shaft 7 carrying a brush 8 which, by the swinging movement of said arm, is moved towards and from the bead ring, which is indicated in position in the machine at 11. Shaft 7 is driven from the main shaft 4 through suitable gearing including the spur gear 9^a fast on the shaft 4 meshing with spur gear 9 carried by a countershaft, which in turn, through chain and sprocket connections indicated at 10, drives the brush shaft 7, whereby the said brush shaft is rotated in a direction reverse to that of the drive shaft 4, the gearing described being housed within the hollow arm. A second brush 2 is carried by, and fast on the drive shaft 4, and lies within the ring and in opposition to brush 8, the two brushes being arranged to act against the bead from opposite sides, and being normally out of contact therewith, as indicated in Figs. 1 to 3, so as to have no action thereon, notwithstanding the fact that they are continuously driven.

The bead ring is supported at points located on opposite sides of the brushes and a material distance therefrom, as shown clearly in Fig. 2, and hereinafter more particularly described, the arrangement being such that when the brush 8 is swung down into contact with the ring 11, and the latter deflected from its true circle and against the brush 2, as shown in Fig. 5, it is abraded from opposite sides by the coaction of the brushes. The brushes are preferably of the wire bristle type, and are most effective when driven so that their peripheries act on the ring in a direction opposed to the direction of travel of the latter, as indicated by the arrows in Fig. 5.

The bead ring is supported in proper relation to the brushes, and drawn there between by the coacting rollers 22 and 19 and the arm 46 carrying bead ring guides 47 and 50, the manner of operating which will now be described.

12 is the feed actuating shaft suitably journaled in the machine frame and driven from shaft 4 at a materially reduced speed by intermediate driving mechanism such as belt drive 13 to shaft 13^a, worm gear 14

connecting shafts 13^a and 18, which latter, through chain and sprocket drive 15 and gear drive 16—17, operates shaft 12. Worm shaft 18 also drives corrugated feed wheel 19 through sprocket chain 20 and bevel gearing 21, but wheel 19 has no feeding effect on the bead ring until the latter is pressed against the feed wheel by the presser roller 22, which is accomplished by the following described mechanism.

Feed shaft 12 rotates within a sleeve 23 (Fig. 2) which carries a cam 24 at one end, and a pawl 25 at the other. This pawl is fulcrumed at 25^b on a fixed pivot and coacts with a ratchet wheel 26 fast on shaft 12 and constitutes a clutch for clutching the sleeve to the shaft, both revolving together when the ratchet wheel is engaged by the shaft, the sleeve remaining otherwise stationary and likewise the cam, and as the cam actuates or controls the feed mechanism in the manner hereinafter described, the feed is controlled by throwing the pawl in or out. Normally the pawl is held out of engagement by a latch 27 fulcrumed at 27^a and engaging a projection 25^a on pawl 25, the pawl being so arranged that when released from the latch it will be caused to automatically engage the ratchet wheel by 30 gravity.

For actuating the latch to release the pawl, I provide a hand lever 28 fulcrumed at 28^a and connected with the latch by link 29. When the operator presses down on 35 the conveniently positioned handle 28^b, latch 27 is forced down until its end rides past or slips over the lug 25^a, whereon the pawl engages the ratchet wheel which couples the sleeve to the shaft and rotates the cam. The 40 release of the handle by the operator allows the latch to be returned to pawl engaging position by the action of spring 27^b, its return movement being limited by stop 27^c.

Thus the depression of handle 28^b clutches 45 or couples the sleeve 23 and cam 24 to the shaft 12, which connection is maintained throughout one complete rotation, or until the pawl is again actuated by the latch 27.

Cam 24 bears against an anti-friction 50 roller 33 carried by one end of a lever 30 fast on shaft 31 journaled in suitable bearings in the machine frame. The opposite end of lever 30 slidably engages, as by a forked push connection, the lower end of 55 a link 34, which constitutes a push rod, and which is connected at its upper end to an arm 35 fast on shaft 38. This shaft carries fast thereon a bell crank lever, one arm 36 of which extends approximately horizontally 60 and is provided with a weight 37, while the other arm 36^a is connected to slide rod 39 mounted to reciprocate in forked bracket 39^a. Journaled on the outer end of rod 39 is a beveled or conical roller 22 which co- 65 acts with drive roller 19, driven through the

bevel gearing 21 in the manner hereinbefore described. Roller 19 preferably has a serrated periphery to assist its frictional engagement with the inner surface of the bead ring, and it is provided with an annular flange 19^a serving as a seat for the ring.

When rod 39 is projected by the bell crank, which occurs when the machine is at rest, the inclined or conical surface of roller 22 is removed from the bead ring so as to render the feed inactive and also to provide ample space between the rollers for the ready insertion and removal of the bead ring, while when the rod is released the action of the weight 37 draws the roller 22 down into contact with the bead ring and forces the latter into contact with the serrated feed wheel.

Shaft 31 also has fast thereon an arm 32 (Fig. 3) to which is attached a sprocket chain 40 which passes upward over a sprocket wheel 43 and has its free end subjected to the pull of tension spring 42, connected to a fixed bracket. This shaft 44, through bevel gears 45, actuates swinging arm 46 pivotally mounted on bracket 46^a, which arm carries spaced bead ring guides 47 and 50, preferably in the form of rollers, the roller 47 having a base flange 47^a to underlie and support the bead ring. When arm 32 is allowed to move upward by the action of the cam, the pull of the spring 42 on the chain rotates shaft 44 in the direction to swing arm 46 downward (towards the left, Fig. 2) into the position shown in Fig. 5 which causes roller 47 to deflect the bead ring from its circular form and press its under surface into contact with brush 2.

Lever 32 has also attached thereto a sprocket chain 41 which passes over a sprocket wheel 48 fast on the hub portion of arm 5. When the lever 32 is permitted to swing upwardly, as above described, the weight of the arm 5 and parts carried thereby, causes the brush 8 to descend from the position shown in Fig. 2 to that shown in Fig. 5.

From the foregoing, it will appear that when the machine is in its inactive condition, the brushes and feed and guide rollers are separated so that a bead ring can be readily placed therebetween, the placing of the bead and its being retained in position being further facilitated and insured by the fact that the various parts are so arranged and disposed that the bead ring is supported in an inclined plane, as shown, the lower portion of the ring resting against an inclined U-shaped supporting frame 51. At this time, with drive belt 1 in operation, brushes 2 and 8, and feed roll 19 are revolving, but being separated, are ineffective as to the bead ring, even if the latter is in place. Shaft 12 is also being continuously driven, but is unclutched from sleeve 23. Depres-

sion of hand lever 28 now releases pawl 25 and allows the same to engage the ratchet wheel 26 and clutch the sleeve to the shaft, which thereupon rotates the cam through 5 one complete rotation at the end of which time the pawl is tripped or withdrawn by the latch, as above described, and the cam stopped. The cam is so shaped that as soon as it starts to rotate, roller 33 rides off the 10 high part of the cam (Fig. 1) onto the low part (Fig. 4), which allows the rollers 22 and 47, and brush 8 to be moved by the spring or gravity means described, into position to act on the bead ring, as hereinbefore described, and the extent of the low 15 part of the cam is such that a complete rotation of the bead ring is effected and its entire surface acted on or abraded by the brushes, whereon the machine automatically 20 stops with the parts held in open position by the high part of the cam, ready for the removal of the buffed or abraded bead ring, and its replacement by a fresh one.

Having thus described our invention, what 25 we claim is:—

1. Apparatus of the class described comprising a pair of normally separated buffing elements, a pair of normally spaced bead core feed wheels on one side thereof, bead 30 core guiding means on the other side of said elements, and means for simultaneously causing said feed wheels to approach each other and said buffing elements to act on the bead core.

35 2. Apparatus of the class described comprising a buffing element journaled to rotate about a fixed axis, a coacting buffing element movable towards and from the horizontal plane of said fixed axis, feeding means 40 on one side of said first named buffing element comprising a pair of normally separated rollers, a presser roller on the opposite side of said first named buffing element for pressing the bead towards the same, and 45 means for simultaneously moving said feed rollers towards each other and said presser roller towards said first named buffing element, and also moving the movable buffing element towards the horizontal plane of the 50 fixed axis of the first named buffing element.

3. Apparatus for the purpose described comprising a rotary buffing element journaled to rotate about a fixed axis, an arm mounted to swing about said axis, a buffing 55 element rotatably mounted in said arm, means for supporting a bead between said elements and progressively feeding it relative thereto, and means for swinging said arm about its axis.

60 4. Apparatus for the purpose described, comprising means for supporting an endless bead ring and progressively rotating the same, a buffing element located within the path of travel of said ring and normally out 65 of contact therewith, and a buffing element

located outside the ring and movable in a path which crosses the line of travel of said ring.

5. Apparatus for the purpose described, comprising means for supporting an endless bead ring and progressively rotating the same, a buffing element rotatable about an axis lying within the path of the ring, an arm mounted to swing about said axis with means for operating it, a rotary buffing element journaled on said arm outside said ring, means for continuously driving said buffing elements, and means for swinging said arm.

6. Apparatus for the purpose described, comprising a buffing element rotatable about a fixed axis, an arm mounted to swing about said axis, a buffing element rotatably carried by said arm, means for supporting a bead ring with a portion lying between said buffing elements, said means including a pair of spaced feed rolls, means for continuously driving said buffing elements and one of said feed rolls, means for moving one of said feed rolls towards the other, and 90 means for swinging said brush-carrying arm.

7. Apparatus of the class described comprising continuously driven buffing means, and means for supporting and feeding a 95 bead ring relative thereto, including means for deflecting the bead ring from its position of rest into contact with said buffing means during the feeding interval.

8. Apparatus of the class described, comprising a rotatable buffing element, means for supporting a bead ring in encircling position relative thereto, but out of contact therewith, said means including means for progressively feeding said bead past the 105 buffing element and means for deflecting said ring into contact with said buffing element.

9. Apparatus of the class described, comprising a rotatable buffing element, means 110 for supporting a bead ring in encircling position relative thereto, but out of contact therewith, said means including feeding means at one side of said buffing element, and a presser roller on the opposite side 115 located outside of said ring, and movable towards and from the periphery thereof.

10. Apparatus of the class described, comprising a rotatable buffing element, means 120 for supporting a bead ring in encircling position relative thereto, but out of contact therewith, said means including feeding means at one side of said buffing element, and a swinging arm on the opposite side, having spaced bead ring guides 125 for engaging opposite sides of the bead.

11. In apparatus of the class described, the combination with a pair of normally spaced apart buffing elements and means whereby they may be caused to act on op- 130

posite sides of a traveling bead, of bead feeding means cooperating therewith comprising a continuously driven feed roller and an idle roller spaced therefrom and 5 movable towards and from the same.

12. In apparatus of the class described, the combination with a pair of normally spaced apart buffing elements and means whereby they may be caused to act on opposite sides of a traveling bead, of bead feeding means cooperating therewith comprising a continuously driven feed roller 10 having an annular bead supporting base flange and an idle roller of approximately 15 conical form journaled on an axis parallel to said feed roller and movable in the direction of its axis.

13. Apparatus for the purpose described, comprising means for supporting a bead ring in inclined position including spaced feed wheels and spaced guides, rotary buffing devices arranged on opposite sides of said ring intermediate of said feed wheels and guides, means for continuously driving 25 said buffing elements and one of said feed wheels, and means for simultaneously moving one of said feed wheels towards the other to grip the bead, moving said guides towards the axis of the ring and swinging the buffing wheel carrying arm.

14. Apparatus for the purpose described, comprising bead supporting means including normally separated feed rollers, continuously driven buffing means arranged to

act on opposite sides of the bead but normally out of contact therewith, yielding means for causing said feed rollers to grip the bead and the buffing means to contact with the bead.

15. Apparatus for the purpose described, comprising bead ring supporting means including normally separated feed rollers one of which is continuously driven, continuously driven buffing wheels arranged to act on opposite sides of the bead and normally spaced therefrom, yielding means tending to cause said feed rollers to feed the bead and the buffing wheels to act thereon, and cam controlled means for rendering said yielding means inactive.

16. In apparatus of the class described, means for supporting and rotating an endless ring, including feed wheels for engaging said ring and progressively feeding the same, at least one of which is continuously driven, continuously driven buffing wheels positioned to act on said ring, but normally out of contact therewith, yielding means tending to cause said feed wheels to grip the ring and said buffing wheels to act 55 on the ring, cam means acting in opposition to said yielding means, and an automatic stop for controlling the action of the cam.

In testimony whereof we affix our signature.

JOSEPH E. PERRAULT.
MALCOLM S. CATE.
